SPRING STRUCTURE

Leonard A. Young, Detroit, Mich.

Application March 14, 1941, Serial No. 383,317

6 Claims. (Cl. 5—260)

This invention relates to improvements in spring structures.

The main objects of this invention are:

First, to provide an improved coil spring structure, including a coil spring assembly or unit characterized by the ease of assembly of the component parts thereof.

Second, to provide a structure incorporating a spring assembly wherein the border coil springs of the assembly are effectively secured to a border frame to resist accidental displacement therefrom or longitudinal movement thereon and to provide an effective border frame which is yieldable to vertical stresses while resistant to lateral stresses.

Third, to provide an assembly or coil spring unit of the foregoing character particularly one employing pocketed or encased springs, whose parts may be readily and quickly assembled by unskilled or inexperienced workers.

Objects relating to details and economies of the invention will appear from the description to follow. The invention is defined in the claims.

Preferred embodiment of the invention are illustrated in the accompanying drawing, in which:

Fig. 1 is a top plan view illustrating a cushion or mattress incorporating the spring assembly or structure of the invention, the upholstered padding being removed in part to illustrate in general manner the relation of the parts of the coil spring assembly.

Fig. 2 is an enlarged fragmentary top plan view further illustrating details of the relation of the parts, so far as the border frame and the connection of the springs to the border frame in the assembly is concerned.

Fig. 3 is a enlarged fragmentary view in section on line 3—3 of Fig. 4.

Fig. 4 is an enlarged fragmentary view in elevation viewed from the interior of the border frame illustrating the final or completed assembly of the spring therewith.

Fig. 5 is a fragmentary view in top elevation illustrating a locking connection for a border frame and spring coil associated therewith in accordance with a modified embodiment of the invention.

Fig. 6 is a fragmentary perspective view illustrating the structure of Fig. 5 in the final or completed stage of the assembly, the position of one of the parts in an intermediate stage being indicated in dotted lines.

Fig. 7 is an enlarged fragmentary view in vertical section illustrating the adaptation of the

principles of this invention in the assembly of pocketed spring with a border frame, whereby the individual pocketed springs are effectively held in desired relation to the frame and one another.

Referring to the drawing, the reference numeral 1 in general indicates a mattress, cushion or other structure incorporating the coil spring assembly of the present invention. This assembly includes annular preferably continuous, top and bottom border frames 3 of resilient steel stock of a generally flat section, the wider surfaces or sides thereof being disposed in the plane of the frame. There are a plurality of coil springs 4 secured to and supported by frames 3 in the manner to be described, these springs being interconnected in a well known manner by the coiled tension connectors or tie elements 5.

20 Referring to Figs. 2, 3 and 4, the end coils of each of the border springs 4 are provided with internally directed loop-like offsets generally designated 6. These offsets are disposed somewhat above or in vertically spaced relation to the plane of the said end coils 4 by the inclined offsets 7 integral with the arms 8 of the loop-like offsets. Arms 8 extend inwardly generally parallel to the plane of the end coils as clearly illustrated in Figs. 3 and 4 and terminate in a bight 9 which is bent downwardly or oppositely to the direction of connecting portions 7.

The border frames 3 are provided with a plurality of spaced slits 10, one for each border spring, and on either side of these slits the material of the frame is upset at outer and inner areas 12, 13 respectively, in opposite directions so as to provide an elongated inwardly opening recess 11 between said areas or portions, which is of substantial vertical and lateral dimensions and adapted to receive the spring offsets 6 and thereby lock and secure springs relative to the frame as well as prevent end shifting relative to the frame.

In assembling the unit the end coils of the border springs 4 are first disposed adjacent the innermost or lower horizontal surface of the frame and are then tensioned radially outwardly, i. e., normal to the periphery of the frame; they are then elevated and canted slightly so as to enable the bight 9 of the loop-like spring offset to be introduced into recess 11 in the frame. So introduced, the inherent spring or the tension on the coil tends to assist in drawing the loop-like offset into the recess, the parts coming to rest in snugly engaged relation as shown

in Figs. 2, 3 and 4 with the offset bight 9 engaging the inner edge of the frame and preventing inadvertent displacement. The foregoing is a structure of exceeding simplicity, yet highly effective in securely engaging the spring and frame. The coacting provisions on the said spring and frame are prefabricated and preconformed in their entirety so that all that is necessary in assembling is a single motion of coil-tensioning and release which is readily and quickly performed by unskilled workers.

In Figs. 5 and 6 I illustrate a slightly modified embodiment of the invention wherein coil springs 14 having uncoformed top and bottom coils are employed. In this embodiment, the border frame 3 is slotted at 10 in the manner described above to provide a coil receiving recess. However, the top coil of the spring is introduced from the inside of the frame by tensioning the same in a direction outwardly normal to the periphery thereof, rather than releasing the same from the outside as in Figs. 1-4. With the coil properly introduced and engaging the upset portion 15, the innermost upset 16 is upset or deformed upwardly and internally of the spring coil, from the dotted line position of Fig. 6, to thereafter maintain the same in a securely locked position relative to the frame. This embodiment has substantial rigidity and is comparatively simple, the only steps in the operation being the introduction of the spring coil and the application of a simple upsetting or distorting blow to the frame.

In Fig. 7 there is illustrated the adaptation of the connection shown in Figs. 5 and 6 for the reception and securement of a pocketed spring 17 encased in a burlap or other fabric casing or pocket 18. It will be appreciated that the coacting upsets 15, 16 of the border frame serve to tension somewhat the material of the pocket or casing 18 and to gather the same at the top between the coacting upset portions, the material itself serving to prevent inadvertent removal of the top coil from the frame, so that it is unnecessary in this case to distort one of the upset portions for this purpose. At the same time the interposed fabric serves as a cushion or silencing material preventing noisy metallic clash at this point.

In the embodiment of the invention illustrated, the structure is reversible—that is, it may be disposed either side up as in a mattress or double-faced cushion. The invention, however, is desirable for embodiment in spring structures of the automobile seat or back or chair cushion type in which a supporting frame is provided for the bottom ends of the springs, the top border frame and the connections of the springs thereto being in accordance with the present invention.

I have illustrated and described the embodiments of my invention which incorporate the principles of the invention in a highly desirable manner. It should be understood that the foregoing terminology is used in a descriptive manner and not in a limiting sense, the scope of the invention claimed being set forth in the following claims.

Having thus described my invention, what I claim as new and desire to secure by Letters Patent, is:

1. A spring assembly of the type described comprising a border frame having a generally flat section disposed with the wider surfaces thereof in the plane of the frame, said frame

having a plurality of elongated slits therein intermediate its inner and outer edges, extending longitudinally of the frame, the material of the latter being distorted in opposite vertical directions on either side of said slits to provide spaced recesses opening laterally of said frame, and a plurality of border springs connected to said frame, the end coils of said springs being provided with inwardly directed loop-like offsets each terminating in a vertically deflected bight adapted to be introduced in one of said recesses between said oppositely distorted frame portions, the offset being laterally positioned by engagement with the ends of the distorted portions and being restrained from outward separating movement relative to the frame by said deflected bight.

2. A spring assembly of the type described comprising a border frame having a generally flat section disposed with the wider surfaces thereof in the plane of the frame, said frame having a plurality of elongated slits therein intermediate its inner and outer edges, extending longitudinally of the frame, the material of the latter being distorted in opposite vertical directions on either side of said slits to provide spaced recesses opening laterally of said frame, and a plurality of border springs connected to said frame, the end coils of said springs being provided with inwardly directed loop-like offsets each terminating in a bight adapted to be introduced in one of said recesses between said oppositely distorted frame portions, the offset being laterally positioned by engagement with the ends of the distorted portions and restrained from movement relative to the frame by said deflected bight.

3. A spring assembly of the type described comprising a border frame having a generally flat section disposed with the wider surfaces thereof in the plane of the frame, said frame having a plurality of elongated slits therein intermediate its inner and outer edges, extending longitudinally of the frame, the portions of the latter on opposite sides of said slits being offset relative to one another to provide spaced recesses opening laterally of said frame, and a plurality of border springs connected to said frame, the end coils of said springs being provided with inwardly directed loop-like offsets extending into said recesses from the exterior side of the frame.

4. A spring assembly of the type described comprising a border frame having a generally flat section disposed with the wider surfaces thereof in the plane of the frame, said frame having a plurality of elongated slits therein intermediate its inner and outer edges, extending longitudinally of the frame, the portions of the latter on opposite sides of said slits being offset relative to one another to provide spaced preformed permanent recesses opening laterally of said frame, and a plurality of border springs connected to said frame, the end coils of said springs being introduced in said recesses between said frame portions, said end coils having substantial overlapping supporting engagement on opposite sides thereof with said respective offset portions, and being laterally positioned by engagement with the ends of the offset frame portions and restrained from movement longitudinally of the frame by said engagement, the frame and a coil positioned thereby having coacting engaging portions retaining and preventing displacement of the coil from the frame in the plane of the latter and normal to the frame.

5. A spring assembly of the type described

comprising a border frame having a plurality of recesses opening laterally of the same, and a plurality of border springs connected to said frame, the end coils of said springs being provided with inwardly directed loop-like offsets each terminating in a vertically deflected bight portion adapted to be introduced in one of said recesses and sprung over an edge of said frame, the offset being laterally positioned by engagement with the ends of the recess and restrained from movement longitudinally of the frame by said engagement.

6. In a spring assembly, the combination of

a plurality of border springs provided with inwardly directed loop-like offsets each terminating in a vertically deflected bight portion, and a border frame having a generally flat section disposed with the wider surface thereof in the plane of the frame, said border frame having a plurality of elongated slits therein providing co-acting pairs of straps, said straps being offset relative to each other, said spring offsets being engaged between said straps with the border frame disposed in subtending relation to the end coils of the springs provided with such offsets.
